UNITED STATES PATENT OFFICE.

S. B. ROWLEY, OF PHILADELPHIA, PENNSYLVANIA.

IMPROVED CAP FOR PRESERVE-JARS.

Specification forming part of Letters Patent No. 74,249, dated February 11, 1868.

To all whom it may concern:

Be it known that I, S. B. ROWLEY, of Philadelphia, county of Philadelphia, State of Pennsylvania, have invented an Improved Cap for Preserving-Vessels; and I do hereby declare the following to be a full, clear, and exact description of the same.

My invention consists in the employment, as a cap for preserve-jars, of a thin metal disk, shaped and corrugated in the manner described hereinafter, so that it may be of increased strength and rigidity.

In order to enable others skilled in the art to make and use my invention, I will now proceed to describe its construction and operation, reference being had to the accompanying drawings, which form a part of this specification, and in which—

Figure 1 is a vertical section of my improved cap and fastener for preserve-jars; Fig. 2 a plan view, and Fig. 3 an exterior view, of the upper end of the jar.

The jar terminates at the top in an annular rib, *a*, which surrounds the mouth *A*, and at the upper edge and exterior of which is a rounded annular projection or lip, *b*, and beneath the latter, on the neck of the jar, is formed a shoulder, *d*, for receiving the gum-elastic ring *e*, the latter being so stretched as to pass over the lip *b* before it reaches its position on the said shoulder.

The cap *B* consists of thin metal, so formed by dies as to have a rounded or dome-shaped top, *f*, with radial corrugations, a central depression, *g*, and a flange, *h*, the latter bearing on the gum-elastic ring *e*.

D is a yoke, made of thin wire, so as to be slightly elastic, and having in the middle an abrupt bend, *m*, adapted to the depression *g* in the cap, the yoke being bent downward at its opposite ends, and these ends being again bent at *x*, so as to catch beneath opposite inclined projections, *y*, on the exterior of the neck of the jar. The top *f* of the cap *B* is corrugated, as shown in Fig. 2, the corrugations radiating from the central depression, *g*, and imparting to the metal, even if the latter be very thin, such a strength that it cannot be forced out of shape by the pressure exerted on it on the application of the yoke, which is simply turned by the hand in the depression *g* as a center until the bent ends *x* catch beneath the projections *y*, and on being moved along the under inclined edges of the same depress the yoke and cap, thus applying to the gum-elastic ring the desired pressure to effect a tight joint, this pressure being continuous, owing to the elasticity of the yoke.

I claim as my invention and desire to secure by Letters Patent—

A cap for preserve-jars, consisting of a thin metal plate, formed and corrugated as specified.

In testimony whereof I have signed my name to this specification in the presence of two subscribing witnesses.

S. B. ROWLEY.
